UNITED STATES PATENT OFFICE.

WILLIAM B. ARNOLD, OF NORTH ABINGTON, MASSACHUSETTS.

BOOT AND SHOE.

1,143,481.

Specification of Letters Patent. Patented June 15, 1915.

Application filed July 20, 1914. Serial No. 851,989.

To all whom it may concern:

Be it known that I, WILLIAM B. ARNOLD, a citizen of the United States, residing at North Abington, in the county of Plymouth and State of Massachusetts, have invented 5 certain new and useful Improvements in Boots and Shoes, of which the following is a specification.

This invention relates to boots and shoes.

Figure 1 is a sectional view of a shoe constructed in accordance with my invention. Fig. 2 is a plan view of what I term the middle sole. Fig. 3 is a plan view of the middle sole, having secured thereto by 10 stitches, or otherwise, the welt at or near the marginal portion of the middle sole. Fig. 4 is a view similar to Fig. 3, showing a form of middle sole where the welt extends entirely around the middle sole and 15 is secured thereto by stitches. Fig. 5 is a cross-sectional view, showing the welt on the middle sole and a reinforcing canvas, or other material, applied to the welt and to the surface of the middle sole. Fig. 6 is a 20 cross-sectional view, showing the middle sole applied to the welt, the dotted lines showing the extension of the middle sole over the welt to be availed of as desired, in connection with the use of metallic or other fastening 25 means.

The upper 1, and the insole 2, can be made and united together by any of the well known or other preferred ways, and such portion of the boot or shoe is not novel 30 with me.

The sole-shaped pattern, or what I term the middle sole 3, may be made of any desired material. This middle sole forms an important part of my invention and of a 40 boot or shoe. By it I am enabled to secure greater flexibility in the methods employed in the manufacture of the shoe, and greater variety in the various modifications of the exact outline of the insole, the bottom of the 45 last and the outsole that is required in the manufacture of boots and shoes, from time to time, for various reasons well known to those skilled in the art of manufacturing boots and shoes, such as, for instance, if it is 50 desirable to have the shoe close on the inside ball, and full on the outside ball, or a decided expression of any part of the outsole, it can be accomplished by so shaping the 55 middle sole as to accomplish this result, after the welt is attached to the margin of the middle sole. By properly shaping the

middle sole I can have the outsole of the shoe close at any point, or full at any point, and secure the various modifications of these two extremes, or any other form that may be desired. This method also produces a shoe where the welt is continued around the heel that is much more desirable than the method at present employed, where the welt goes only to the forepart of the heel, as the 60 welt can be continued around the heel by attaching it to the middle sole thus completing the shoe, that is stitched around the heel with a single operation. To the edge of the marginal portion of this middle sole 3, I secure a welt strip 4. This welt strip 4 may be attached to the marginal portion of the middle sole by stitches, as shown, or it may be cemented, the essential point being that the middle sole serves as a pattern by which 65 to modify, as desired, the outlines as fixed by the insole and the bottom of the last, and to carry out such modification of the welt in proper position for attachment to the insole, and for the attachment of the outsole to the welt. The middle sole 3, with its welt 4 attached in any desired way, is placed in a proper position upon the insole, and the welt 4 secured to the insole by means of stitches, staples, or any other preferred 70 form of permanent fastening means. Thereafter, the outsole is secured to the welt in any well known or preferred way.

While I have shown in the drawings a 75 welt 4 as a single piece of material, it may be, of course, made of two or more superimposed strips, such as leather, for instance, and fabric, and the latter if employed, may extend beyond the edge of the leather welt to reinforce the latter.

The fabric strip in addition to being extended beyond the margin of the welt strip 4, may also extend over the whole or any part of the middle as a reinforcement for the middle sole.

In cases where metal fastenings are employed, for securing the welt to the insole, the outline of the middle sole may be extended sufficiently to permit the fastenings to pass not only through the welt, but also 90 through the margin of the middle sole itself, in order to give it strength, and such provisions may be employed for any form of fastening means, as desired.

Having thus explained the nature of my 110 invention and described a way of constructing and using the same, though without at-

tempting to set forth all of the forms in which it may be made, or all of the modes of its use, what I claim and desire to secure by Letters Patent is:—

- 5 1. A boot or shoe comprising an upper and in-sole, a middle sole, a welt arranged upon the middle sole and projecting beyond the margin thereof, fastening means connecting said middle sole, welt and in-sole, an out-sole, and fastening means connecting the latter to the margin of said welt.
- 10 2. An article of manufacture comprising a middle sole and a welt, said welt being arranged upon and secured to said middle

sole and having its outer margin projecting ¹⁵ beyond the outer margin of said middle sole.

15 3. An article of manufacture comprising a middle sole, a welt secured to the marginal portion thereof, and a fabric reinforce ²⁰ secured to said welt and middle sole.

In testimony whereof, I have affixed my signature, in presence of two witnesses.

WILLIAM B. ARNOLD.
